CLAIM

I claim the ornamental design for a silt fence installing machine, as shown and described.

DESCRIPTION

FIG. 1 is a left rear perspective view of a silt fence installing machine showing my new design;
FIG. 2 is a front elevation thereof;
FIG. 3 is a rear elevation thereof;
FIG. 4 is a left end view thereof;
FIG. 5 is a right end view thereof;
FIG. 6 is a top view thereof; and,
FIG. 7 is a bottom view thereof.
